UNITED STATES PATENT OFFICE

CHARLES GUERITEY, OF PASSAIC, NEW JERSEY

SIFTING TOP CAN

Application filed August 16, 1927. Serial No. 213,336.

This invention relates to cans or similar receptacles for holding material in powdered form, the construction being such that this material may be either sifted out through perforations or poured out through a large pouring opening. Various constructions have been provided for such receptacles whereby a slide is applied to the top, which in one position permits of sifting out the contents and in another position permits of pouring out the contents, and in a third position closes the respective openings, so that the contents are confined. The present invention provides certain improvements in cans or receptacles of this character.

According to this invention the slide is imperforate and the can top is formed with two openings, the one a large pouring opening and the other a sifting opening, consisting of a group of perforations; these respective openings are arranged close enough together to be covered by the slide in its normal mid-position; the slide is movable to either side so that moved in one direction it uncovers the sifting perforations and moved in the other direction it uncovers the pouring opening. Stops are formed to limit these respective movements of the slide. The openings are formed in a portion of the can top which is either elevated above the seam which unites the top to the can body or at least is no lower than the top of this seam; the slide is extended laterally and passes freely over the top of the double seam, which latter as usual is formed to project exteriorly and the slide is then bent down on each side to embrace the seam and turned underneath the seam. This construction gives a resilient engagement between the slide and the can top, such as holds it firmly in any position, while yet permitting it to be freely slid from one position to another. The can top instead of being recessed is extended at least flush with the seamed top of the can or preferably slightly above that level, so that no hollow is afforded for collecting dust.

The improved construction is shown in the accompanying drawings, wherein, —

Figure 1 is a perspective view of the improved receptacle.

Fig. 2 is a plan of the top thereof.

Fig. 3 is a cross section of the top on the line 3—3 in Fig. 2.

Fig. 4 is a cross section at right angles to Fig. 3 on the line 4—4 in Fig. 2.

Fig. 5 is an enlarged fragment of Fig. 4.

A is the can or other receptacle, being preferably made of tin (tinned sheet iron), as usual, although other materials are suitable. The top B is united to the body A in the usual manner by a double seam *a*. The bottom C is similarly united to the body by the usual double seam *b* or in any other way. D is the slide which is simply a band of metal passing across the top of the can top and having its side portions *c* turned down close against the outside of the seam *a* and bent under it at *d*. The portion *c* is corrugated or knurled to give a better hold for shifting the slide.

The can top B is formed with its main portion *e* preferably on a level with or at least not materially lower than the top of the seam *a*; and with a portion *f* which is slightly raised above the portion *e*. This portion *f* is formed with a pouring opening *g* and with sifting perforations *h*, the latter constituting collectively a sifting opening. The slide D lies in a plane close above the elevated portion *f* of the can top, as best shown in Fig. 5, and is thence extended laterally to meet the downturned portions *c*. This lateral extension may be perfectly flat, as shown, or it may more or less approach the level of the portion *e*, but should in any event pass clearly and freely over the top of the double seam *a*. It results from this construction that the portion of the slide D indicated at *i* in Fig. 5 which extends over the general level *e* of the can top and between the raised portion *f* and the downturned side portions *c* of the slide constitutes a sort of resilient bridge whereby in cooperation with the downturned portions *d* the slide is held down in place to form a tight fit over the perforated portion *f*, so as to tightly close the openings and at the same time to form a yielding engagement with the side *100*

seam *a* which constitutes its slideway. Heretofore such slides have been made to closely fit around the seam, embracing it at both top and bottom, a construction which 5 is liable to generate too much friction, particularly after a can has been long held in storage, so that the metal has become slightly corroded. My improved construction is not affected by any slight corrosion resulting from storage, and the slide is enabled to work freely at all times, while yet having sufficient cling to the can top to hold it securely in any position in which it may be left.

15 In case the flanged portions *c*, *d*, of the slide become stuck fast, the resilient bridges *i* enable the operator, by pressing down the outer portions of the slide, to free them from any adherence to the seam; the space 20 between the top of the seam and the under side of the slide being sufficiently wide to enable pressure thus applied to force the undeturned hooked portions *d* away from the seam; thus the slide may easily be re- 25 stored to free sliding relation.

The openings, *g*, *h*, are close enough together and the slide *D* is wide enough so that in the middle position of the slide both openings are closed. When it is desired to 30 pour the contents from the can, the slide is pushed to the left, as shown in Fig. 2, thereby uncovering the pour hole *g*. When it is desired to sift out the contents the slide is moved to the right, as shown in Fig. 1, 35 thereby uncovering the perforations *h*. These opposite movements of the slide are limited by stop projections *E E* which are bent up from the otherwise level top of the can slightly above the slide.

40 In the construction of the can the can top and body are seamed together in the usual way. At this time the can top is devoid of the stop projections *E E*. The slide *D* is then applied by slipping it over the can top 45 from one end. Then by inserting a suitable die or punch within the can body the projections *E E* are struck up; this retains the slide and prevents its being disconnected from the top. Then with the slide in its 50 intermediate position the can is turned bottom side up and filled with powder through its open bottom. Thereafter the bottom head is applied and seamed on to the body in the customary manner.

55 Heretofore cans of this general type have usually had the top depressed to a level of about that of the lower portion of the double seam. This leaves a hollow or depressed portion in the can top which in the case of 60 goods which stand long on a grocer's shelves, for example, is liable to accumulate dust and present an unsightly appearance. Because of the dust lodging in this recess it is impossible to wipe it off and it is generally impracticable to turn over such a can to the 65

purchaser in neat condition after it has been held a considerable time on the shelves. The present invention avoids this disadvantage by forming the can top with its portion *e* substantially flush with or not materially 70 lower than the top of the double seam. This involves a somewhat unusual construction in that the metal of the can top inside of the seam (which usually is carried inward in the position shown by dotted lines *x* in Fig. 75 5) is bent upward at *j* to a height substantially equal to the top of the double seam, and is then carried inward on the level *e*. The portion *j* is bent in so close to the double seam as to leave only an extremely narrow 80 crack between, which is too thin to admit any appreciable amount of dust. The result is that the can top appears to be and is substantially flush with the top of the seam, so that there is no opportunity for the accumulation of dust in a position where it cannot be readily wiped or brushed off.

85 The construction shown is that which is preferred, but this may be somewhat varied within the limits of the appended claims.

90 What I claim is:

1. A receptacle having its top double-seamed to its body, the top having openings, and the portion of the top formed with such 95 openings raised above the bottom of such seam, and a slide having its middle portion lying close above the said portion of the top to close one or more of said openings according to its position and having resilient lateral portions extended freely above said 100 seam and bent down against and under said seam to resiliently embrace the seam, whereby they may be sprung down to release their cling under said seam.

2. A powder receptacle having pouring 105 and sifting openings in its top, and the top and body united by a double seam, the top formed substantially flush with the upper part of such double seam to avoid the formation of a hollow or recess in which dust 110 may collect.

3. A receptacle for powder having sifting and pouring openings in its top and the top double seamed to the body, the top formed with an upward bend closely adjacent to 115 such seam, whereby the main part of the top is elevated to a plane substantially flush with the top of the seam.

4. A receptacle for powder having its top double-seamed to its body, the top having 120 openings, and the portion of the top formed with such openings raised above the level of such seam and a slide having its middle portion lying close above the said portion of the top to close one or more of said openings according to its position, and having its lateral portions extended freely beyond such 125 elevated top and above the top of the seam, and bent down against and under said seam to form a sliding fit with the latter, the 130

space between the top of the seam and the bottom of the slide enabling the resilient lateral portions of the slide to be pressed down to separate its under portion from the seam,
5 whereby to keep the parts in sliding relation.

5. A receptacle having its top formed with an opening in the form of perforations for sifting, and having a large opening for
10 pouring and a slide movable to three positions to open either or close both of said openings, the receptacle having its top seamed to its body, and the slide having resilient lateral portions extended freely
15 above said seam on both sides and bent down against and under said seam to resiliently embrace the seam, whereby they may be sprung down to release their cling under said seam.

20 In witness whereof, I have hereunto signed my name.

CHARLES GUERITEY.
